THREAD CONTROL FOR WEFT
REPLENISHING LOOMS

Richard G. Turner, Worcester, Mass., assignor to
Crompton & Knowles Loom Works, Worcester,
Mass., a corporation of Massachusetts

Application December 14, 1942, Serial No. 468,930

22 Claims. (Cl. 139—256)

This invention relates to improvements in thread control mechanism for weft replenishing looms and it is the general object of the invention to provide improved mechanism for removing the thread of the outgoing bobbin at the time of transfer.

When the depleted bobbin is expelled from the shuttle of the weft replenishing loom the thread extending from it to the selvage may be drawn into the shed to form a thick place in the fabric unless removed. In my prior Patent No. 2,199,296 I have shown pneumatic means for removing this thread including a pneumatic tube between a thread cutter near the shuttle eye and the selvage which draws the thread end adjacent to the cutter out of the path of the shuttle. Several picks after transfer the template cutter severs the thread and it is then drawn away from the lay and moved into a container. In the aforesaid patent the pneumatic tube is moved to operating position by the transerrer arm as the latter descends and the tube is returned to its normal raised position as the lay reaches back center.

It is an important object of my present invention to hold the pneumatic tube stationary and provide means to lift the thread and cause it to move into the zone of operation of the pneumatic remover by mechanism which is brought into operation at the time of transfer.

It is still another object of my present invention to provide the pneumatic tube with a thread catching lip which is notched to receive the thread lifter, which may conveniently be made of wire, so that the inrushing stream of air is on both sides of the wire to attract the end of the thread which extends from the wire to the shuttle and also the end which extends to the selvage.

As the shuttle enters the shuttle box the thread extends from the front wall of the shuttle to the selvage, and as the lay reaches front center position to beat the thread to the fell the thread extends diagonally outwardly and forwardly because of the fact that the front wall of the shuttle is in front of the fell by a distance equal to the width of the shuttle. It is another object of my present invention so to relate the intake mouth of the pneumatic thread remover and the wire with respect to the fell and front wall of the shuttle as to cause the thread to move along the wire to a position in front of the intake mouth while the wire is still down, and then raise the wire at or near front center to permit it to enter the aforesaid notch. As a

result of this construction backward motion of the lay will draw the thread along the wire toward the intake mouth.

The type of loom to which my invention more particularly applies employs a normally stationary lever which is raised preparatory to transfer for the purpose of setting the transfer latch and also moving a transfer revoker into position to prevent transfer should the shuttle be improperly placed. It is a still further object of my present invention to provide a trip lever mechanism for controlling the position of the thread lifter wire including an arm which is normally raised but is depressed when the main lever of the mechanism rises to set the magazine for transfer. As this latter lever completes its upward movement a part of the trip lever mechanism acts to release another part which controls the wire and the latter thereupon rises to lift the thread toward the intake mouth. The trip lever mechanism includes a hook which moves to releasing position through operation of the main cam and resetting is effected when the main lever descends.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a loom having my invention applied thereto,

Fig. 2 is an enlarged view of a portion of Fig. 1 but viewed from the center of the loom,

Fig. 3 is an enlarged vertical section on line 3—3 of Fig. 1,

Fig. 4 is a plan view of the structure shown in Fig. 3,

Fig. 5 is an enlarged vertical section on line 5—5 of Fig. 3,

Fig. 6 is an enlarged vertical section on line 6—6 of Fig. 1,

Fig. 7 is a view similar to Fig. 3 but with the parts in a different position,

Fig. 8 is a detailed plan view showing the relation between the shuttle, the thread, and my invention when the lay is on front center, and

Fig. 9 is a vertical section on line 9—9 of Fig. 2 on an enlarged scale showing the lower end of the thread extractor which is used with my invention.

Referring to Fig. 1, the loom frame 15 supports top and bottom shafts 16 and 17, respec-

tively, which rotate in the direction of arrows *a* and *b*, the top shaft 16 completing a rotation every pick of the loom and the bottom shaft completing one rotation in two picks. The lay 18 is attached by connectors 19 to cranks 20 on the top shaft and swings backwardly and forwardly about the rocker shaft 21.

The lay is provided with a shuttle box B having a box front 22 shown as a binder provided with an opening 23 to receive a thread cutter 24. The shuttle S when in the box B is connected to the selvage L by means of a thread T which extends into the box along the front wall of the shuttle between the latter and the box front 22 and across the opening 23 in position to be severed by the cutter 24. The lay when on the front center position shown in Fig. 8 has the reed R at the fell F of the cloth and the box back 25 is in forward position aligned with the fell so that the thread T is inclined to the right and forwardly.

The magazine M may be of the rocking multi-color type and is mounted on a pivot 30 held in fixed position in the upper part of the loom. Operating connections designated generally at 31 connect the magazine to a hook 32 which can be positioned for operation by a stud 33 on a normally stationary lever 34 but mounted on a fixed stud 35 at the bottom of the loom for limited rocking movement. A second lever 36 also on stud 35 has a regularly recurring movement the cycle of which is completed in two picks of the loom. This latter lever carries a stud 37 which enters a groove of the cam 38 secured to the bottom shaft 11. A dog 39 on lever 36 normally clears a lifting lug 40 on lever 34, but when a replenishing operation of the loom is to occur the dog is moved to the left as viewed in Fig. 6 by one or the other of two dog placers 41 and 42, the latter being shown in Fig. 6 in indicating position to cause the dog 39 to move under lug 40 as lever 36 rises.

An air pump 45 is held in fixed position on the loom frame and has a piston 46 driven by a rod 47 connected to the upper end of the lever 48 which turns about a fixed pivot 49 on the loom frame. A connector 50 between lever 48 and the lay is the means by which piston 46 is caused to move back and forth in timed relation with the lay to create a partial vacuum in the cylinder to the left of the piston as viewed in Fig. 6 on backward strokes of the lay. A pneumatic tube 51 leads forwardly from the front of the air pump and is connected to a thread accumulator 52 held in fixed position on the loom frame. A second pneumatic tube 53 leads from the bottom of the accumulator toward the center of the loom to be attached to a pneumatic thread remover to be described hereinafter.

The magazine includes a transfferer arm 55 with its latch 56 to be engaged by a bunter 57 on the lay. A rod 58 extends upwardly from the forward end of lever 34 and is connected to a rocking head 59 on fixed stud 60. The head has a latch lifter 61 and a shuttle position detector 62. The weft detector 63 is of the electrical type and is connected to a solenoid 64 having a plunger 65 which operates the mechanism shown in Fig. 6. The detector operates when the lay is at front center and the shuttle is on the magazine side of the loom, and in indicating weft exhaustion operates by the well-known mechanism shown in Fig. 6 to throw one or the other of the dog placers into dog engaging position, depending upon which shuttle is active.

The loom operates with two shuttles either of which can be replenished from the magazine M, the shuttle boxes not shown at the opposite end of the loom from that shown in Fig. 1 being connected by a flexible link 66 to a rocking lever 67 movable about a fixed stud 68 on the bracket 69 secured on the outer end of stud 35. It is by means of lever 67 that the hook 32 is moved either into or out of the path of the stud 33 when the right end of lever 34 descends incident to a weft replenishing operation. For further understanding of the matter thus far described reference may be had to prior Patent Nos. 2,199,-353, 2,199,296, 2,162,290 and 2,199,354.

In the operation of the mechanism thus far described the lay reciprocates as usual and the shuttle is picked first from one side of the loom and then to the other, entering box B on alternate picks of the loom. On each backward stroke 10 of the lay the pump creates a partial vacuum in tube 53 tending to draw any weft thread in it toward the accumulator 52. The lever 34 is normally idle and is rocked only on transferring beats of the loom to cause upward movement of the left end of the lever as viewed in Fig. 1. The cutter 24, which is normally in forward idle position, moves through the opening 23 against a plate 70 on the front wall of the shuttle to cut the thread between the selvage and the shuttle delivery eye on transferring beats. That part of the thread of the outgoing bobbin to the right of the cutter as viewed in Fig. 8 moves down out of the shuttle box with the depleted bobbin, but the end of the thread 20 extending to the left of the cutter must be removed otherwise it will be drawn into the shed and it is this part of the thread to which my invention more particularly relates.

In carrying my invention into effect I secure the end of the tube 53 remote from the accumulator to a thread extractor tube 75 mounted on a rod 76 movable forwardly in a stand 77 secured in fixed position on the loom, preferably to the stud 78 which supports the transfferer arm 55. 25 The rod 76 carries a collar 79 to receive the rearward thrust of a compression spring 80 the forward end of which bears against a bearing 81 formed as part of the stand 77. A second bearing 82 on the stand limits rearward movement 30 of the collar and together with bearing 81 guides rod 76. As distinguished from prior constructions shown in certain of the aforesaid patents, the rod 76 in the present instance is held in fixed position and the extractor tube 75 is normally in 35 the position shown in Fig. 2 and will remain in that position unless struck by a misplaced shuttle, at which time the spring 80 yields to prevent breakage.

A thread placer 85 which may take the form 40 of a flexible steel wire has the forward end thereof anchored as at 86 to a part of the loom frame, such as the breast beam 87, and has the rear part thereof attached to a spring 90 the rear end of 45 which is supported by a clip 91 secured to the loom frame. The wire has secured thereto a small rod head 92 held adjustably along the wire by a set screw 93. A light weight rod or wire 94 is secured to the rod head and extends downwardly to operating mechanism which normally 50 permits the head to be raised but acts at the time of transfer to lower the head and therefore the wire 85. Spring 90 is strong enough to hold wire 85 taut and also sustain the weight of rod 94 and parts connected thereto to be described, holding 55 the rod and parts normally raised.

The mechanism connected to rod 94 is shown more particularly in Figs. 3, 4, 5 and 7 and includes a stand 100 secured to the loom frame and supporting a fixed stud 101. Front and back levers 105 and 106, respectively, as viewed in Fig. 3, are mounted on the stud 101, lever 105 having a hub 107 which receives the rear end of a torsion spring 108 the forward end of which is held by a collar 109 adjustable angularly on the stud and held in fixed position thereon by a set screw 110. Spring 108 tends to turn lever 105 clockwise as seen in Figs. 3 and 7. An arm 112 of lever 105 carries a depending stem 113 having a cross head 114 for engagement with a lifter 115 secured to lever 34. The torsion spring holds the cross head 114 against the lifter, and since the forward end of lever 34 is normally down, the left end of lever 105 will be normally raised, as shown in Fig. 3.

Lever 106 has a hub 120 rotatable freely on the stud 101 and is attached as at 121 to the lower end of the rod 94. A lug 122 secured to lever 106 is positioned for engagement with a trip mechanism 123 on lever 105 which comprises a lever 124 having an upright arm 125 formed with a hooked head 126 for engagement with the lug 122. A horizontal arm 127 of lever 124 carries a vertically adjustable releasing screw 128 for engagement with an adjacent fixed part of the loom frame 15. The lever 124 is mounted on a stud 130 secured to lever 105 and the upright arm 125 is held against a stop 131 on lever 105 by a compression spring 132 the left end of which bears against the arm 125 and the right end of which bears against a lug 135 on lever 105.

In the operation of the invention thus far described, the thread placer or wire 85 is normally up and is high enough above the path of the shuttle not to interfere with picking. The spring 90 holds the wire 85 up and also maintains the lever 106 in raised position with the lug 122 under the head 126 of the trip mechanism. Under these conditions the lever 34 is normally down so that the arm 112 is in low position.

When a transferring operation is to occur lever 34 is rocked by the dog 39 so that the left end thereof as viewed in Fig. 1 is raised to set the transfer latch and shuttle position detector in transfer position. This upward movement occurs while the lay is still in rear position and before the depleted shuttle enters the shuttle box. When the lever 34 rises the lifter 115 raises the cross head 114 and rocks lever 105 in a counter-clockwise direction from the position of Fig. 3 downwardly toward the position of Fig. 7, and during this movement the hooked head 126 lowers the lever 106 so that the rod 90 and rod head 92 are depressed. The wire 85 is therefore lowered, moving into a transverse slot 140 on the lay to a position below the shuttle path. As the shuttle enters the box its thread T will pass over the wire 85.

The shuttle is ordinarily boxed approximately at bottom center with the lay near the midpoint of its forward travel. The parts are so timed that after the shuttle is boxed continued downward movement of lever 105 due to the raising of the forward end of lever 34 will cause release screw 128 to engage the loom frame, whereupon the lever 124 rocks in a clockwise direction as viewed in Fig. 3 and moves to the position in Fig. 7, thereby releasing the lug 122. Since lever 106 is free to turn on stud 101, the spring 90 immediately lifts the left end of lever 106 as soon as the latter is released by the trip mechanism, and the

wire 85 is raised to its normal position, lifting the thread T with it as it rises.

When the shuttle enters box B the thread T is in the shed behind the fell of the cloth and 5 also behind the extractor 75. As the lay moves forwardly to beat up the weft the thread assumes the diagonal position shown in Fig. 8 and moves forwardly to a position in front of the extractor 75 before the trip mechanism releases lever 106. The raising of wire 85 is therefore delayed until the lay has reached a sufficiently forward position to place the thread in front of the extractor 75. The thread is then cut in the 10 shuttle box incident to a transferring operation, and as the lay moves rearwardly the right end of the thread as viewed in Fig. 8 also moves backwardly along the raised wire 85 toward the extractor and reaches the latter before the shuttle is picked. The air pump acts to create a partial 15 vacuum within the extractor during backward movement of the lay, and therefore as the shuttle is picked that part of the thread extending from the extractor 75 toward the shuttle box is drawn into the extractor, having been placed favorably for this operation by upward motion 20 of the wire 85 and also the rearward movement of the lay. At some subsequent time the thread is cut at the selvage by a temple cutter C, after which the whole piece of thread is drawn into the extractor and moved into the accumulator cylinder 52.

An important feature of my invention relates to the lower end of the extractor 75, particularly the relation between the extractor and the 35 thread placing wire 85. As shown in Fig. 9 the extractor tube 75 is provided with a downwardly extending lip or stop 150 preferably behind the intake mouth 151 in the bottom of the extractor tube. This lip is notched as at 152 to receive the thread placing wire 85. The notch is 40 preferably centrally located with respect to the mouth so that air drawn into the extractor will travel along both sides of the thread placing wire. The lip extends below the wire when the latter is in 45 raised position and it is for this reason that as the lay recedes and the thread travels along the wire it will be drawn to a position closely adjacent to and under the intake mouth where it will be held or trapped by the combined action 50 of the lip and the placing wire until it is drawn into the extractor. I have shown the lip as an extension of the tube of which the extractor is made, but I do not wish necessarily to be limited to this particular form, since it is sufficient 55 if a stop extends below the thread placing wire when the latter is raised adjacent to the intake mouth to position the thread correctly with respect to the extractor.

The release mechanism which has been 60 described in connection with Figs. 3 and 7 will operate satisfactorily with the types of cam previously used on the bottom shafts of looms to which this invention more particularly relates, but it is preferable where possible to give the 65 forward end of lever 34 a slight additional upward movement beyond that which is otherwise necessary for setting the magazine for transfer for the purpose of insuring movement of the hooked head 126 away from the lug 122. I may 70 therefore form the cam 138 with a slight rise 160. This part 160 of the cam does not engage the stud on lever 36 until after rod 52 has had its required upward movement to set the magazine for transfer and the slight additional upward movement of the forward end of lever 34

does not interfere with the proper operation at the proper time of the other parts of the loom which are controlled by the rod 53.

In the foregoing I have described a pneumatic system operated by a lay actuated pump acting to create a partial vacuum in the intake mouth during backward movement of the lay. I do not wish thus to be limited in the practice of my invention, however, as a stream of air can be drawn continuously into the intake mouth by replacing pump 45 with a rotary pump, or by connecting tube 53 to a vacuum system.

From the foregoing it will be seen that I have provided means by which the extractor tube 75 can be held in stationary position and the thread lifted to a position where it can be drawn into the intake mouth. The wire 85 will be below the thread at the beginning of the operation of the mechanism, and the thread placer will rise preferably late enough in the forward movement of the lay to permit the thread to have moved to a position in front of lip 150 and the intake mouth. It will also be seen that the thread placing wire cooperates with the lip 150 of its equivalent during backward movement of the lay to direct the thread to a position closely adjacent to the intake mouth. It will be seen that I provide a trip lever mechanism which acts due to movement of the usual lever 34 to permit the wire 85 to rise at the correct time in the loom cycle while the thread is in front of the intake mouth. It will also be noted that the timing of the mechanism is such that the wire 85 rises to trap the thread in front of the notched lip of the extractor 75 before the pick which immediately follows transfer, and because of this relationship there is no danger that the thread extending between the wire 85 and the thread cutter will be drawn by the shuttle into the warp shed.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay provided with a shuttle box containing a shuttle from which a thread extends to the adjacent selvage, a pneumatic thread remover having a stationary intake mouth in front of the lay and into which a draft of air is drawn to attract a thread into the remover, a thread placer extending transversely of the lay from a point in front of the intake mouth rearwardly toward the path traversed by the shuttle, and means operative on a replenishing beat of the loom to raise the thread placer from a position below said mouth and below the path traversed by the shuttle after the latter and the thread connected thereto has passed over the placer to a position adjacent to said intake mouth to lift the thread toward said intake mouth after the thread due to advance movement of the lay has moved to a position forward of said intake mouth.

2. In a weft replenishing loom having a backwardly and forwardly reciprocating lay provided with a shuttle box containing a shuttle from which a thread extends to the adjacent selvage, a pneumatic thread remover having a stationary intake mouth in front of the lay and into which a draft of air is drawn to attract a thread into the remover, a thread placer extending from a point in front of the intake mouth rearwardly toward the path traversed by the shuttle, a member having a movement incident to a weft replen-

ishing operation of the loom, and means controlled by said member and operative subsequent to passage of the shuttle and the thread connected thereto over said placer as the shuttle enters said box to raise the placer from a position below said shuttle path and below the intake mouth to a position adjacent to said intake mouth to lift the thread toward said mouth during the latter part of the forward movement of the lay.

3. In a weft replenishing loom having a backwardly and forwardly reciprocating lay provided with a shuttle box containing a shuttle from which a thread extends to the adjacent selvage, a pneumatic thread remover having a stationary intake mouth and into which a draft of air is drawn to attract a thread into the remover, an elongated thread placer extending transversely of the lay, means to support the forward end of said placer at a point in front of said intake mouth, a member having a movement incident to a replenishing operation of the loom, a lifter for said placer, and means connected to said placer and operated by said member to cause said lifter to raise the placer from a position below the path of the shuttle and below said intake mouth to a position adjacent to said intake mouth after said shuttle and the thread connected thereto has passed over the placer in the movement thereof toward said shuttle box during the latter part of the forward movement of the lay to move said thread toward said intake mouth.

4. In a weft replenishing loom having a lay provided with a shuttle box containing a shuttle from which a thread extends diagonally rearwardly to the adjacent selvage when the lay is in forward position, a pneumatic thread remover having a stationary intake mouth in front of the lay and into which a draft of air is drawn to attract a thread into the remover, said intake mouth being located rearward of the thread when the lay is in forward position, a thread placer for said thread having the forward end thereof supported with respect to the loom frame at a point forward of the intake mouth, a lifter for said thread placer, a member having a movement incident to a replenishing operation of the loom, and mechanism controlled by said member and cooperating with said lifter to effect upward movement of said placer from a position below the path of the shuttle after the latter and the thread connected thereto have passed over the placer prior to entry into said shuttle box subsequent to movement of the thread to a position forward of said intake mouth due to forward movement of the lay to move said thread to a position adjacent to said intake mouth.

5. In a weft replenishing loom having a lay provided with a shuttle box containing a shuttle from which a thread extends to the adjacent selvage, a pneumatic thread remover having a stationary intake mouth forward of the lay and into which a draft of air is drawn to attract a thread into the remover, said thread extending diagonally forwardly from the fabric toward said shuttle box when the lay is in front position and said intake mouth being located rearward of the thread when the lay is in forward position, a member having a movement incident to a replenishing operation of the loom, a controller for said placer operated by said member when the latter has said movement to locate the placer in a position below the path of the shuttle as the latter approaches said shuttle box on a replenishing beat of the loom, a lifter normally tending to raise said placer, and trip mechanism op-

eratively connected to said controller and operated by said member subsequent to movement of the shuttle and thread connected thereto over said placer as the shuttle approaches said box to enable said lifter to raise the placer after the thread due to advance movement of the lay has moved to a position forward of said intake mouth, said lifter raising the placer to a position adjacent to said mouth and causing said placer to raise the thread to a position in front of said intake mouth.

6. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, said thread extending diagonally forwardly from the fabric toward said shuttle box when the lay is in front position and said intake mouth being located rearward of the thread when the lay is in forward position, a thread placer for said thread, means to support the forward end of said placer at a point forward of said intake mouth, a member having a movement incident to a replenishing operation of the loom, a lifter for said placer tending normally to hold said placer in a position adjacent said intake mouth, and controller mechanism for the placer operated by said member when the latter has said movement and effective to move said placer against the action of said lifter to a position below the path traversed by the shuttle before the latter reaches said placer as the shuttle approaches said box and subsequently release said placer to enable the lifter to raise said placer after the shuttle has passed over said placer when travelling toward said shuttle box to enable the lifter to raise said placer to move the thread to a position in front of said intake mouth after the thread due to forward movement of the lay has reached a position forward of said intake mouth.

7. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, a thread placer extending rearwardly from a position in front of the intake mouth toward the path traversed by the shuttle as the latter approaches said box, a thread stop depending from said thread remover and rearwardly of said intake mouth, a member having a movement incident to a replenishing operation of the loom, a lifter for said placer, and mechanism controlled by said member and effective by a force derived from said member when the latter has said movement to locate the placer below the path of the shuttle and below said stop when the shuttle approaches said box and effective thereafter due to continued movement of the member to release said placer after the shuttle and the thread connected thereto has passed over said placer when moving toward said box to enable said lifter to raise the placer after the thread due to advance movement of the lay has reached a position forward of said holder and cause said placer to lift the thread to a position in front of said stop and intake mouth.

8. In a weft replenishing loom having a lay provided with a shuttle box containing a shuttle from which a thread extends to the adjacent selvage, a pneumatic thread remover having a stationary intake mouth in front of the lay and into which a draft of air is drawn to attract a thread

5 into the remover, a thread trapping lip extending downwardly from the remover behind the intake mouth, a thread placer, a support for the forward end of the placer located at a point in front of said lip, said placer extending rearwardly from said support toward the path traversed by the shuttle, a member having a movement incident to a weft replenishing operation of the loom, and moving mechanism for the placer under control of said member and including a part to locate the placer below said lip and under the path traversed by the shuttle as the latter approaches said box on a replenishing beat of the loom and said moving mechanism including also a lifter to raise said thread placer subsequent to passage of the shuttle over said placer as the shuttle approaches said box to raise the thread to a position above the bottom of said lip to locate the thread in a position above said placer and in front of said lip and intake mouth.

9. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, a lip projecting downwardly from said remover behind the intake mouth, said lip having a downwardly opening notch intermediate the sides of the intake mouth measured in the direction of the length of the lay, a thread placer extending rearwardly from a point in front of said lip toward the path traversed by the shuttle, a member having a movement incident to a weft replenishing operation of the loom, and control mechanism for the placer including a depressor for the placer to locate the latter below said lip out of said notch and below the path of the shuttle as the latter approaches said shuttle box on a replenishing beat of the loom to cause the shuttle and thread connected thereto to pass over the placer, said control mechanism including also a lifter to raise the placer after the shuttle has passed over said placer when moving toward the shuttle box on a replenishing beat of the loom to elevate said placer to a position within said notch and cause said placer to lift the thread to a position above said placer and in front of said lip and intake mouth.

10. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, two members capable of cooperating to form a thread trap adjacent to said intake mouth, one of said members being permanently located behind said mouth and the other member being movable vertically with respect to the first member, and control mechanism for said other member to move the latter below the path of the shuttle to cause the latter to pass over said other member on replenishing beats of the loom and locate said other member below said first member, said control mechanism including also a lifter operative subsequent to movement of the shuttle over said other member to lift the latter to lift the thread to a position in front of the first member and cause said members to cooperate to form said thread trap.

11. In a weft replenishing loom having a lay provided with a shuttle box containing a shuttle from which a thread extends to the adjacent selvage, a pneumatic thread remover having a

stationary intake mouth into which a draft of air is drawn to attract a thread into the remover, a thread placer extending in a direction transversely of the lay, a member having a movement incident to a replenishing operation of the loom, lifter means tending normally to raise the placer to a position adjacent to said intake mouth, and trip lever mechanism operatively connected to the placer and located for movement by said member on replenishing beats of the loom and operative first to lower said placer against the action of said lifter means to a position below the path of the shuttle and thereafter release said placer to enable the lifter means to raise the placer after the shuttle has passed beyond said 15 placer in its movement toward said shuttle box for the purpose of raising the thread toward said intake mouth.

12. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, a thread placer, a member having a movement incident to a replenishing operation of the loom, a lifter for said placer tending normally to hold the latter raised and adjacent to said mouth, and trip lever mechanism including a part operatively connected to said placer, a second part positioned for operation by said member when the latter has said movement and a releasable third part normally connecting the first two parts to cause the latter to effect movement of the placer to a position below the path of the shuttle on replenishing beats of the loom when said member has said movement, said third part thereafter operative to release the first two parts to enable said lifter to raise the placer to lift the thread toward said mouth after the shuttle has passed said placer in the movement thereof toward said shuttle box.

13. In control mechanism for the thread placer of a weft replenishing loom having a member which moves incident to a replenishing operation of the loom and having a pneumatic thread remover provided with an intake mouth, said control mechanism comprising a lifter normally tending to hold the placer near said intake mouth, and said mechanism including trip lever means having one part operatively connected to the placer, having a second part positioned for a placer depressing movement by said member, and having a third part normally connecting the first two parts but moved by a force derived from said member to disconnect said first and second parts, said third part when in normal position causing the first part to effect movement of the placer against the action of said lifter when the second part has a depressing movement.

14. In control mechanism for the thread placer of a weft replenishing loom having a member moving incident to a replenishing operation of the loom and having a pneumatic thread remover provided with an intake mouth adjacent to the normal position of said placer, said control mechanism comprising a lifter tending normally to hold said placer adjacent to said mouth, and said control mechanism also comprising two levers one of which is operatively connected to the placer and the other of which is located for operation by said member, and a trip forming part of said control mechanism normally connecting the two levers but movable by a force derived from said member to disconnect said levers.

15. In thread control mechanism for a weft replenishing loom having a pneumatic thread remover provided with an intake mouth and a thread placer movable with respect to said intake mouth, means tending normally to maintain the thread placer adjacent to said mouth, trip lever mechanism comprising two levers normally connected by a detent which is movable from normal position to release said levers from each other, one of said levers operatively connected to said placer, an operating member for the weft replenishing loom, a cam having an incline operatively related to said member during a weft replenishing beat of the loom to give said member a movement against said other lever to effect down motion of the placer with respect to said mouth by a force transmitted through said detent, said cam having a second incline to give said member a further movement in said given direction, and stop means to cooperate with said detent during said further movement of said member to move said detent from normal to disconnecting position relatively to said levers and release said one lever to enable the lifter to raise said one lever and thread placer.

16. In thread control mechanism for a weft replenishing loom having a pneumatic thread remover provided with an intake mouth and a thread placer movable with respect to said intake mouth, lifter means tending normally to maintain the thread placer adjacent to said mouth, trip control mechanism for said placer comprising two levers and a detent normally connecting said levers, one of said levers being operatively connected to the placer to effect down movement of the latter away from said intake mouth when the other lever has a depressing movement, an operating member positioned for engagement with and operation of said other lever, and a cam operatively connected to said member during a replenishing beat of the loom and having an incline to cause said member to give a depressing movement to said other lever when said levers are connected by said detent to cause the first lever to effect down movement of the placer away from said intake mouth, said cam having a second incline effective to give said member a further movement after the placer has been moved by the first lever to a position below said intake mouth, and stop means for said detent to cause movement of the latter during said further movement of the member to release said levers and enable the lifter means to raise the first lever and said placer to locate the latter in normal position with respect to the intake mouth independently of said other lever.

17. In thread control mechanism for a weft replenishing loom having a lay provided with a shuttle box containing a shuttle from which a thread extends to the adjacent selvage, said loom having normally idle parts settable to operating position preparatory to a replenishing operation of the loom, said parts when set in operating position effective during the latter part of forward movement of the lay to effect replenishment, a pneumatic thread remover having a stationary intake mouth, a thread placer normally adjacent to said intake mouth, an operating member having two successive movements in the same direction and connected to said parts and effective during the first of said successive movements to set said parts for replenishment, and control mechanism for said thread placer operatively interposed between said member and

said placer and comprising disconnectable elements one of which is operatively connected to the placer and the other of which is positioned for engagement by said member during both of said successive movements thereof, said member during the first of the successive movements thereof on a replenishing beat of the loom causing said disconnectable elements to effect downward movement of the placer away from said intake mouth when said member is setting said parts for a replenishing operation of the loom, said control mechanism being so constructed that said operating member during the second of said successive movements thereof effects disconnection of said elements subsequent to initiation of the replenishing operation of the loom to enable said lifter to return said thread placer to the normal position thereof adjacent to said intake mouth.

18. In thread control mechanism for a weft replenishing loom having a reciprocating lay provided with a shuttle box to receive a shuttle from which a thread extends in a diagonal direction rearwardly and toward the selvage when the lay is in front center position so that a portion of said thread is in front of the lay, the loom having provision for cutting the thread in the shuttle box on replenishing beats of the loom, a pneumatic thread remover having a stationary thread intake mouth located between the shuttle box and selvage and behind the thread when the lay is on front center, a thread placer extending transversely of the lay, means to cause the thread placer to be under the path traversed by the shuttle when the latter approaches the shuttle box on transferring beats of the loom to cause the thread to pass over the placer, and means thereafter to raise the thread placer after the thread due to advance motion of the lay has moved forwardly along said placer to a position forward of the intake mouth to raise the thread to a position in front of the intake mouth and cause said thread by the backward movement of the lay to move rearwardly along said placer to the intake mouth.

19. In thread control mechanism for a weft replenishing loom having a reciprocating lay provided with a shuttle box to receive a shuttle from which a thread extends in a diagonal direction rearwardly and toward the selvage when the lay is in front center position so that a portion of said thread is in front of the lay, the loom having provision for cutting the thread in the shuttle box on replenishing beats of the loom, a pneumatic thread remover having a stationary

thread intake mouth located between the shuttle box and selvage and to the rear of the thread when the lay is on front center, a normally raised thread placer extending transversely of the lay adjacent to the intake mouth, means operative incident to a replenishing operation of the loom to lower the thread placer to a position below the shuttle path to cause the shuttle and thread to pass over the placer, and means to raise the thread placer to lift the thread to a position in front of the intake mouth after the thread by reason of the advance motion of the lay has moved forwardly along said placer, the subsequent backward movement of the lay prior to the pick immediately following transfer causing the thread to move rearwardly along said placer to the intake mouth.

20. A pneumatic thread intake tube for a loom operating with a thread placer movable toward and from the tube, said tube comprising a hollow member provided with a thread receiving mouth, and a lip on the tube adjacent to said mouth and notched to receive said placer.

21. A pneumatic thread intake tube for a loom operating with a thread placer movable toward and from the tube, said tube comprising a hollow member provided with a thread receiving mouth, and a depending lip on said tube behind the intake mouth formed with a downwardly opening notch to receive said placer.

22. In a weft replenishing loom having a lay provided with a shuttle box containing a shuttle from which a thread extends to the adjacent selvage, a pneumatic thread remover having a stationary intake mouth into which a draft of air is drawn to attract a thread into the remover, an elongated thread placer extending transversely of the lay and having the front end thereof forward of said intake mouth and having the rear end thereof back of said intake mouth, means to mount said thread placer for rising and falling movement toward and from said intake mouth, a member having a movement incident to a replenishing operation of the loom, and control mechanism for said placer operated by said member and effective to cause said placer to have an upward movement throughout the length thereof from a position below the shuttle path to a position adjacent to the intake mouth after the thread due to advance movement of the lay has moved along said placer to a position forward of the intake mouth for the purpose of lifting said thread toward said intake mouth.
